UNITED STATES PATENT OFFICE.

JOHN T. SCHAAFF, OF WASHINGTON, DISTRICT OF COLUMBIA.

TYPE-WRITER AND OTHER KEY-CONTROLLED MACHINE.

1,040,584.

Specification of Letters Patent.

Patented Oct. 8, 1912.

Application filed September 4, 1902, Serial No. 122,078. Renewed September 20, 1904. Serial No. 225,263.

To all whom it may concern:

Be it known that I, JOHN T. SCHAAFF, of Washington, in the District of Columbia, have invented certain new and useful Im-
5 provements in Type-Writer and other Key- Controlled Machines, of which the following is a specification.

My invention relates to typewriting and other key controlled machines, and one of 10 the primary objects thereof is to provide a machine which may instantly and without the removal or addition of any parts be converted from the character of machine in which the type bars or other operated 15 parts are impelled by means other than the power used in depressing the keys, or force with which the keys are depressed into a machine of that character in which the operation of the operated parts is effected by 20 the power or force with which the keys are depressed or vice versa.

The Cahill electric typewriting machine is a representative of the first type of machine referred to, while the Remington type- 25 writing machine is a representative of the second type of machine.

The many advantages possessed by a convertible typewriting machine over either the type of machine in which the operation 30 of the type bars is dependent solely upon power auxiliary to that employed for depressing the keys or the type of machine in which the operation of the type bars is dependent solely upon the power employed for 35 depressing the key levers, will suggest themselves; but among others, it may be well to mention that a machine capable of being converted as described, avoids the objection which is so often urged against the type of 40 machine which I have designated as of the first class, this objection being that the machine is rendered inoperative and useless the moment the auxiliary power is cut off for any reason.

45 Another primary object of the present invention is to provide a simple and satisfactory electrically operated mechanism for impelling the type bars to the printing point upon the depression of the keys pertaining 50 thereto which includes means for permitting the return of the type bars and the keys to their initial positions independently of one another.

Another object is to provide a typewriting machine having pivoted type bars with 55 electrically operated mechanism so positioned that long link connections may be interposed between said bars and the operating levers coupled thereto to reduce torsional strain upon said links and there- 60 through lessen the strain upon the type bars which tends to pull the same out of their positions.

Other objects of the invention will suggest themselves when the same is more fully 65 explained.

With the objects specifically set forth and many others in view which will appear and be fully appreciated when the invention is made clear, the same comprises the novel 70 construction, combination and arrangement of parts which will be hereinafter described and particularly pointed out in the claims.

While the invention is susceptible of various modifications I have illustrated in the 75 accompanying drawings what I now conceive to be the preferred embodiment of the same.

In these drawings—Figure 1 is a vertical sectional view of a typewriting machine embodying my invention showing the parts in the positions assumed thereby when the machine is set to be operated by means auxiliary to that employed for depressing the keys. Fig. 2 is a similar view showing the 80 parts in the positions assumed thereby when the machine is set to be operated solely by the power employed in depressing the keys. Fig. 3 is an end elevation of one of the arms employed in the improved mechanism. Fig. 85 4 is a similar view of a modification of said arm. Fig. 5 is a perspective view of one of the push fingers. Fig. 6 is a detail perspective view. Fig. 7 is a detail sectional view of a modification of my invention, and, Fig. 90 8 is a plan view of one of the key levers employed in this construction.

The invention is illustrated in the accompanying drawings, and will be hereinafter described as embodied in the construction of 100 typewriting machines having pivoted type-bars, as certain subordinate features of the invention have special reference to this particular construction of machine, and presents special combinations with certain parts 105 thereof, but it will be understood that most

of the primary features of the invention are applicable by slight modification, well within the range of the invention, to various types of machines, such for instance, as the construction of machine in which the type-bars have a thrust movement in traveling toward and from the printing point.

As before premised, in the present invention, mechanism is provided for impelling the typebars to the printing point either by a power auxiliary to that employed for depressing the keys or by the power with which the keys are depressed. In the particular embodiment of the invention illustrated in the accompanying drawings and to be hereinafter described, electricity is utilized as the auxiliary power, and the mechanism for utilizing the same to secure the operation of the machine will first be described, and thereafter will be described the converters and action of the mechanism when the machine is converted into one in which the type bars are impelled solely by force or power employed for depressing the keys.

For the purpose of accentuating the salient features of the invention in illustrating the same as embodied in the construction of typewriting machines hereinbefore referred to, certain of the well-known parts of said machines have been eliminated.

In these drawings a section of the platen is shown at *a*, the machine frame at *b*, two of the type bars pivoted to the upper plate 35 thereof and depending thereinto at *c*, *d*, a buffer ring for the latter at *e*, and the keys at *f*. The key lever pertaining to each key *f*, preferably includes a lever proper *g*, having the key connected directly thereto, and 40 an auxiliary lever *g'* having the type bar pertaining to the key coupled thereto through the intermediary of an adjustable link *i*.

In order to obtain a uniform pull upon the type bars in the operation of the machine, 45 the auxiliary links *g'* are preferably pivoted in staggered relation to one another, those connected to one set of type bars represented by the bar *c*, being pivoted approximately centrally of the machine at *z*, while 50 those coupled to the remaining type bars represented by the bar *d* are pivoted at the rear of the machine at *z*.

Pivoted directly to each auxiliary lever *g'* near the front end of the same is a bell-crank lever *m*, the vertical arm of which 55 coacts with the motor frame *n* to be herein-after described, while the horizontal arm *m'* of said lever constitutes the setting or positioning member thereof. The levers *m*, when 60 inactive are held by springs *o*, in rearwardly tilted positions, as illustrated in Fig. 1, in which positions the upper ends of the vertical arms *m'* are held out of the path of movement of the motor frame *n*.

65 The motor frame *n* is disposed in a hori-

zontal position, having its side member pivoted at one end upon a shaft *n'* supported in bosses or studs *n*², while the free end of said frame is provided with a contacting surface *n*³, extending entirely across the machine and designed when the frame is drawn down, as will be described, to strike against the end of the vertical arm *m'*, of the lever *m* positioned in the path thereof, and depress the same and therethrough the auxiliary lever *g'* pertaining to the positioned lever *m* and through the link *i* actuate the type bar coupled to the lever *g'*. One side member of the motor frame *n* is preferably provided with an angular extension or depending arm *n*⁴, which is coupled by an adjustable link *p* to the core of a horizontally arranged sucking magnet *r*. The latter is arranged in a normally dead circuit including a generating unit *s*, stationary contact point *s'*, and a universal contact frame *t* carrying a contact point *t'*, designed to contact with the point *s'*. The frame *t*, which is pivotally supported, preferably by arms *u* which are themselves pivotally supported by lugs *E* for a purpose to be hereinafter explained, is provided with a flexible arm extending to the rear of its pivot, carrying the point *t'* and with a cross bar *t*² extending entirely across the machine arranged to coact with the vertical arms *n* pivotally connected at their lower ends to the links *g* which carry the same. An arm *u* is associated with each link *g*, and the free end thereof is normally held in a rearwardly tilted position by a spring *u'* associated therewith to normally maintain the shoulder *v* of said arms above and in engagement with the cross bar *t*², and a shoulder *v'* formed on said arm in engagement with a lateral extension *m*³ on the free end of the arm *m*² of the bell crank lever *m* associated with the lever *g'* pertaining to the lever *g* to which the arm *u* is pivoted. Each arm *u* is provided with an offset guide opening *u*² 100 designed to receive the end of the lever *g'* pertaining thereto, and each lever is provided with a beveled portion, preferably the end thereof, designed when the lever is depressed, to coact with the end of the bottom wall of said guide opening to throw the arm *u* pertaining thereto, forward against the tension of its spring *u'* to release the contact frame and position lever *m*, as will be hereinafter described.

Upon the depression of one of the keys *f*, the lever *g* carrying the same is depressed, carrying with it the arm *u* pivoted thereto, the latter being in engagement with the cross bar *t*² of the universal contact frame *t*, and 110 with the extension *m*³ of the lever *m* associated therewith, and rocks the lever *m* against the tension of its spring *o*, bringing the end of the arm *m*² thereof into the path of the contacting surface *n*³ of the motor 115

120

125

130

frame n , and simultaneously tilts the frame t , and closes the circuit through the magnet r by bringing the point t' into contact with the point s' . The magnet, being energized, instantly sucks in its core, drawing the free end of the arm n^4 rearwardly, and therethrough throws down the free end of the motor frame n bringing the contacting surface n^3 thereof into engagement with the end of the arm m' of the positioned lever m depressing the latter, and therethrough depressing the lever g' , to which said positioned lever m is pivoted, thus operating the type bar pertaining to the key depressed, through the intermediary of the link connection between said type bar and the lever g' referred to. In the downward movement of the lever g' , the beveled end w thereof contacting with the rear edge of the bottom wall of the guiding opening u^2 of the arm u carried by the depressed key lever g throws said arm u forward against the tension of its spring u' and thereby disengages the shoulders v and v' thereof from the cross bar t^3 of the universal contact frame t , and the positioned lever m , respectively. As soon as the frame t is released, the same is returned to its initial position by the spring t^4 interrupting the electrical circuit through the magnet r at the points s' , t' , thus deenergizing the magnet and permitting the motor frame n to reassume its initial position under the influence of the spring n^5 . The lever m , upon being released is at once restored to position by its spring o and the auxiliary lever g' is restored to position by the spring g^3 associated therewith.

The restoration of the parts described to their initial positions takes place notwithstanding the fact that the key f may be held depressed but as soon as the same is released by the operator, said key and lever carrying the same is restored to position by the spring g^2 associated therewith. It will be particularly noted that the return of the key and the lever carrying the same, takes place entirely independent of the return of the type bar, and thus should either said key and lever, or said type bar stick, it would not effect the return to their initial positions of the other operating elements.

After the arm u is thrown forward against the tension of its spring u' disengaging the same from the universal contact frame and the extension m^3 of the lever m , said arm is held out of engagement with said parts until the key lever carrying the same is restored to its initial position, so that should the key lever become stuck and thus hold down the arm u , the latter will not interfere in any way with the operation of the other keys of the machine.

To hold the arm out against the tension of its spring u' until the key lever carrying the same is restored to its initial position, the

front end or nose v^2 of the arm u is designed to coact with the front end of the part m^2 or extension m^3 of the latter. It will be appreciated that upon the arm u being thrown out, the lever g' at once returns to its initial position and that the nose v^2 will remain in engagement with the front end of said part m^2 or the extension m^3 thereof as long as the key lever g remains in its depressed position and as a consequence said arm u will be held forward so as not to interfere with the universal contact frame or the levers m carried by the other keys.

From the above description, it will be understood that the movement given to the finger key by the operator, serves to shift the arm m' into position to be struck by the motor frame and also by effecting the closing of the circuit, causes the magnet to be actuated. The magnet, when actuated by the closing of the circuit, effects a movement of the motor frame which, in turn, striking the positioned arm m' , moves it and the auxiliary lever, to which it is connected, downward, the movement of the auxiliary lever, through its connections with the type bar, causing the type bar to be actuated. The devices operated by the magnet to thus actuate the type bar, move independently of the movement of the finger key and return to initial position independently of the movement of the finger key.

As before premised, the present invention contemplates the provision of means for instantly converting the machine from one in which the mechanism interposed between the keys and type bars is employed for operating the latter when actuated by the depression of the former by power auxiliary to that employed for depressing said keys such as has just been described, into one in which said mechanism is employed for operating the type bars by the power or force used in depressing said keys. In the construction illustrated in the accompanying drawings, this object is attained by merely coupling the levers g to the auxiliary levers g' pertaining thereto, so that the two operate as a single part or as one key lever. To this end, means are provided for maintaining the arms u in their rearward positions with the shoulders v' thereof in engagement with the upper faces of the extensions m^3 of the levers m , the latter being thrown forward to seat said extensions upon the upper edges of the levers g' pertaining thereto, as indicated in Fig. 2.

As the universal contact frame t is rendered unnecessary in the converted machine, means are preferably provided for shifting its cross bar t^3 out of the path of the shoulders v , and as the levers g , g' , are coupled to move in unison, the springs g^3 associated with the latter are sufficient to restore said levers to their initial positions, after the

same are depressed and released, and consequently the springs g^2 are rendered unnecessary and in fact undesirable, and therefore means are also provided for throwing said springs out of operation.

5 For throwing the levers m' forward, and at the same time retracting the contact frame t , a rocking frame 1, is preferably provided, comprising side arms 4, pivotally supported in lugs 2, and a cross bar 3 extending across the machine connecting said side arms arranged to the rear of the levers m to provide, when the machine is arranged to be electrically operated, a stop or rest for the arms m' . The contact frame t is carried by the side arms 4, being pivotally connected to the same below the pivotal axis thereof. Any suitable means may be provided for rocking the frame 1 from the position shown in Fig. 1, into the position shown in Fig. 2, said frame when rocked into the latter position serving to throw the bar 3 against the arms m' of the levers m to hold the latter in advanced positions, the extensions m^3 of the arms m^2 thereof, coacting with the edges of the levers g' to provide stops for said arms and to retract the contact frame t to withdraw the bar t^3 thereof out of the paths of the shoulders v of the arms u . While the bar 3 is preferably made use of to throw the levers forward to occupy their advanced positions, said bar can be dispensed with so far as this function thereof is concerned as the arms u , when drawn down, as will be hereinafter described, when the machine is set for manual operation only, will perform this function ascribed to said bar.

10 The springs g^2 are carried by a rocking bar g^6 , operated by a lever g^8 , arranged at the rear of the machine, said springs being lowered out of contact with the under edges of the levers g by tilting the lever g^6 forwardly.

15 For holding the arms u in their rearward positions with the shoulders v' thereof in engagement with the extensions m^3 of the arms m^2 of the levers m , an eccentrically journaled cross shaft 5 is preferably provided. This shaft as shown in the accompanying drawings in addition to providing means for holding the arms u in their rearward positions also provides a stop for arresting the upward movements of the levers g under the ends of the return springs 20 thereof.

25 To avoid lost motion in the connection between each lever g and the auxiliary lever g' pertaining thereto, when the machine is set for manual operation only, means are provided for normally holding the levers g in a lower plane than that occupied by the same when the machine is set to be operated by power auxiliary to that employed for depressing the keys, thereby holding the 30 arms u in lower positions so that the shoul-

ders v' thereof will be maintained in direct engagement with the lateral extensions m^3 and the latter maintained in direct engagement with the edges of the levers g' . To arrest the levers g' on the return thereof in 35 their different positions the cross shaft 5, before referred to, is preferably provided with two stop surfaces 6, 7. The surface 6 also coacts with the links u , and when said shaft 5 is turned to bring the latter surface into 40 action as shown in Fig. 2, the levers g are held in their lowermost return positions, and the arms u are held in their rearward positions. When the shaft 5 is turned to carry the surface 6 out of action, as shown 45 in Fig. 1, the arms u are released and the surface 7 is brought into action to provide a stop for the levers g in a relatively higher plane than the stop therefor provided by the surface 6.

50 When the machine is arranged to be operated by means auxiliary to the power employed for depressing the keys, it is desirable that the latter have but a slight dip, while when the machine is converted, as described, a relatively deeper dip of the keys is desired. To this end an adjustable stop for limiting the depression of the keys is desirable, and in the embodiment of this 55 feature of the invention hereinafter disclosed, a stop bar 10, which is common to all of the key levers, is provided, this bar being eccentrically mounted between the sides of the machine frame, and being provided with two arresting surfaces 10^a , 10^b . When the bar is turned, as shown in Fig. 1, the surface 10^a performs the function of the stop, and but a slight dip of the keys is provided for. To obtain a maximum dip, the bar 10 is turned to bring the same into the position illustrated in Fig. 2, in which position the surface 10^b provides the arresting surface. When the machine is set for manual operation only, the auxiliary levers g' are coupled by the arms u to the levers g pertaining to the same, so that the two move as one part, and consequently upon the depression of a key, the movement thereof is directly transmitted to the type bar pertaining to the same, the electrically operated mechanism remaining inactive.

60 In Fig. 7 a modified embodiment of my invention is illustrated. In this form of the invention, the arms which are utilized to set in action the electrically operated mechanism upon the depression of the keys pertaining to the same, when the machine is set to be electrically operated, and for directly operating the supplemental levers coupled to the typebars on the depression of the key levers pertaining thereto, when the machine is set to be manually operated, are supported by and depended from members employed for actuating the universal contact frame, and for positioning the push finger; the free 65

ends of such arms having detachable engagement with the key levers with which the same are associated.

Referring particularly to Fig. 7, the key levers are indicated by the letter g^{10} , with each of which a bell crank lever h^{10} is associated, the latter being mounted upon a common cross-rod h^{11} , supported at its ends in opposite sides of the machine frame. To the free end of the horizontal arm of each lever h^{10} , an arm m^{10} is pivotally connected, the free end of the latter being provided with a shoulder m^{11} designed to engage with an off-set or an abutment g^{11} projecting laterally from the key lever associated therewith. Each key lever is also provided with an off-set finger g^{12} in advance of the abutment carried thereby which provides a guide for the free end of the arm m^{10} associated with the same, as will be hereinafter described. Pivoted at its lower end to each supplemental lever g^{14} is a push finger o^{10} coupled by a link p^{10} to the vertical arm of the bell crank lever h^{10} pertaining to the same; the connection between said link and the vertical arm of the bell crank lever h^{10} being preferably a sliding pivotal one formed by an elongated slot in the link in which a pin projecting laterally from the end of the vertical arm of the bell crank lever works. The push fingers o^{10} are, as in the embodiment of my invention first described, held out of the path of movement of the motor frame r^{10} which is actuated by the sucking magnet s^{10} upon the closing of the normally open electrical circuit which includes said magnet, the line t^{10} , a generating unit t^{11} , rheostat t^{12} , fixed contact point t^{13} and universal contact frame t^{14} . The bell crank levers h^{10} are normally held up in the position in which the same are shown in Fig. 7 by a suitable spring, the free end of each arm m^{10} is held in engagement with the off-set g^{11} pertaining thereto by a spring m^8 interposed between the pivoted end of said arm and the bell crank lever h^{10} carrying the same, and the push fingers o^{10} are normally held out of the path of movement of the frame r^{10} by a spring o^{11} which is interposed between each of said fingers and the supplemental lever g^{14} carrying the same. Upon the depression of the key lever g^{10} , the bell crank lever h^{10} pertaining thereto is rocked in the direction indicated by the arrow, through the interposed arm m^{10} . The horizontal arm of the bell crank lever coming into engagement with the universal contact frame serves to depress the latter and therethrough close the electrical circuit. The movement of said bell crank lever through the interposed link p^{10} simultaneously positions the finger o^{10} pertaining to the key lever depressed. The magnet being energized upon the closing of the electrical circuit as before described, actuates the

motor frame r^{10} which depresses the supplemental lever g^{14} pertaining to the key manually operated, through the intermediary of the positioned push finger. In the downward movement of the supplemental lever g^{14} the inclined end g^{16} thereof comes into contact with a lateral abutment m^{12} on the arm m^{10} which is held down by the depressed key lever g^{10} and serves to throw said arm m^{10} forward, disengaging the free end thereof from the off-set g^{11} of said depressed lever. As soon as the arm is released the bell crank lever h^{10} is restored to its initial position by its spring releasing the contact frame which is also restored to its initial position as the electrical circuit is broken when the contact frame is released and thus the positioned push finger is freed, the latter being also restored to its initial position by a spring associated with the same.

As in the first described embodiment of my invention, to set the machine to be operated manually, the universal contact frame is shifted out of the path of its operating members, and the key levers are arranged to be operated in a lower plane than the machine is set to be electrically operated. The contact frame as shown herein is eccentrically mounted or pivotally supported from a rotatable disk t^{15} , the operation of which throws the cross-bar of said contact frame into and out of the path of movement of the horizontal arms of the bell crank levers h^{10} .

As in the preferred embodiment of my invention a rocking frame g^{17} common to all the key levers g^{10} is provided for limiting the return movement of the key levers. When this frame is turned to bring the working face g^{18} thereof into coaction with the key levers, the latter are forced down until the pins m^{14} of the arms m^{10} are seated in recesses in the upper edges of the supplemental levers g^{14} . The supplemental levers are thus, through the interposition of the arms m^{10} and pins m^{14} depressed when the key levers are actuated independently of the electrically operated mechanism.

The construction and operation of my typewriting machine will be readily understood upon reference to the foregoing description and accompanying drawings, and it will be understood that the parts and combinations recited may be varied within a wide range without departing from the spirit of the invention. It will be also understood that while the invention is herein shown and described as a part of a typewriting machine, I do not intend to limit it to use in such machines as it is evident that it may be applied to any key controlled machine in which an operated part is caused to impinge upon its objective point as for instance in linotype or matrix making ma-

chines, piano actions and the like equally well as to a typewriting machine.

I claim—

1. In a key controlled mechanism; the combination of a key and an operated part, a normally inactive motor, means controlled by the key for causing the motor to be actuated, means movable independently of the movement of the key, operated by the motor, for actuating the operated part and means for actuating the operated part directly by the key.
2. In a typewriting machine, the combination of a key and a type bar, a normally inactive motor, means controlled by the key for causing the motor to be actuated, means movable independently of the movement of the key, operated by the motor, for actuating the type bar and means for actuating the type bar directly by the key.
3. In a key controlled mechanism, the combination of a key and an operated part, a normally inactive motor comprising a fixed and a reciprocating part, means controlled by the key for causing the motor to be actuated to effect movement of the reciprocating part, means movable independently of the movement of the key, operated by the motor, for actuating the operated part and means for actuating the operated part directly by the key.
4. In a typewriting machine, the combination of a key, and a type bar, a normally inactive motor comprising a fixed and a reciprocating part, means controlled by the key for causing the motor to be actuated to effect movement of the reciprocating part, means movable independently of the movement of the key, operated by the motor, for actuating the type bar, and means for actuating the type bar directly by the key.
5. In a key controlled mechanism, the combination of a key and an operated part, a normally inactive motor, means normally controlled by the key for causing the motor to be actuated, means movable independently of the movement of the key, operated by the motor, for actuating the operated part, means for disconnecting the motor controlling means from the key and means for actuating the operated part directly by the key.
6. In a typewriting machine, the combination of a key and a type bar, a normally inactive motor, means normally controlled by the key, for causing the motor to be actuated, means movable independently of the movement of the key, operated by the motor, for actuating the type bar, means for disconnecting the motor controlling means from the key and means for actuating the type bar directly by the key.
7. In a key controlled mechanism, the combination of a key and an operated part, a normally inactive motor, means normally

controlled by the key for causing the motor to be actuated, means movable independently of the movement of the key, operated by the motor, for actuating the operated part, means for limiting the movement of the key when the motor controlling means is connected therewith, means for disconnecting the motor controlling means from the key and means for actuating the operated part directly by the key.

8. In a typewriting machine, the combination of a key and a type bar, a normally inactive motor, means normally controlled by the key for causing the motor to be actuated, means movable independently of the movement of the key, operated by the motor, for actuating the type bar, means for limiting the movement of the key when the motor controlling means is connected therewith, means for disconnecting the motor controlling means from the key and means for actuating the type bar directly by the key.

9. In a key controlled mechanism, the combination of a key and an operated part, a lever normally independent of the key, connected with the operated part for actuating the same, a normally inactive motor, means controlled by the key for causing the motor to be actuated, means movable independently of the movement of the key, operated by the motor, for operating the lever to actuate the operated part, and means for operating the lever directly by the key.

10. In a key controlled mechanism, the combination of a key, and a type bar, a lever normally independent of the key, connected with the type bar for actuating the same, a normally inactive motor, means controlled by the key for causing the motor to be actuated, means movable independently of the movement of the key, operated by the motor, for operating the lever to actuate the type bar and means for operating the lever directly by the key.

11. In a key controlled mechanism, the combination of a key carried by a key lever, and an operated part, a supplemental lever connected with the operated part for actuating the same, a normally inactive motor, means controlled by the key for causing the motor to be actuated, means movable independently of the movement of the key, operated by the motor, for operating the supplemental lever to actuate the operated part, and means for mechanically connecting the key lever and supplemental lever.

12. In a typewriting machine, the combination of a key carried by a key lever, and a type bar, a supplemental lever connected with the type bar for actuating the same, a normally inactive motor, means controlled by the key for causing the motor to be actuated, means movable independently of the movement of the key, operated by the motor, for operating the supplemental lever to actu-

18. In a typewriting machine, the combination with a key, a typebar, an electrically operated power mechanism arranged, when operated, to actuate the typebar, a normally open circuit including said power mechanism, means normally arranged to be operated by the key to close said circuit, means for disconnecting said circuit closing mechanism from the key, and means for directly connecting the key and typebar. 75
19. In a typewriting machine the combination of two key levers, each pivoted to the frame of the machine, the pivots of the two key levers being substantially in line, two type bars, one pivoted to the frame of the machine, forward of its center, and the other pivoted to the frame in rear of its center, auxiliary levers connected respectively with the typebars, the auxiliary lever connected with the typebar which is pivoted to the frame forward of its center, being pivoted to the frame at a point forward of the point at which the other auxiliary lever is pivoted, the two auxiliary levers having their forward ends substantially in line, and means for connecting the auxiliary levers respectively at their forward ends, with one of the key levers, means comprising coupling devices pivoted to the key levers and arranged substantially in line for connecting the auxiliary levers, respectively with the key levers. 85
20. In a typewriting machine, the combination of two key levers, each pivoted to the frame of the machine, the pivots of the two key levers being substantially in line, two typebars, one pivoted to the frame of the machine, forward of its center, and the other pivoted to the frame in rear of its center, auxiliary levers connected respectively with the typebars the auxiliary lever connected with the typebar which is pivoted to the frame forward of its center, being pivoted to the frame at a point forward of the point at which the other auxiliary lever is pivoted, the two auxiliary levers having their forward ends substantially in line, and means for connecting the auxiliary levers respectively at their forward ends, with one of the key levers means comprising coupling devices pivoted to the key levers and arranged substantially in line for connecting the auxiliary levers, respectively with the key levers. 95
13. In a key controlled mechanism, the combination of a key and an operated part, a lever connected with the operated part for actuating the same, a normally inactive motor, means controlled by the key for causing the motor to be actuated, means movable independently of the movement of the key, operated by the motor, for operating the lever to actuate the operated part, and means operated by the lever for causing the motor to again become inactive immediately upon the actuation of the operated part. 100
14. In a typewriting machine, the combination of a key and a type bar, a lever connected with the type bar for actuating the same, a normally inactive motor, means controlled by the key for causing the motor to be actuated, means movable independently of the movement of the key, operated by the motor, for operating the lever to actuate the type bar, and means operated by the lever for causing the motor to again become inactive immediately upon the actuation of the operated part. 105
15. In a key controlled mechanism, the combination of a key and an operated part, a lever connected with the operated part for actuating the same, an electrically controlled power mechanism arranged in a normally open circuit, circuit closing means arranged to be operated by the key to close the circuit, means movable independently of the movement of the key operated by the power mechanism for operating the lever to actuate the operated part and means operated by the lever for breaking the circuit immediately upon the actuation of the operated part. 110
16. In a typewriting machine, the combination of a key and a type bar, a lever connected with the type bar for actuating the same, an electrically controlled power mechanism arranged in a normally open circuit, circuit closing means arranged to be operated by the key to close the circuit, means movable independently of the movement of the key, operated by the power mechanism, for operating the lever to actuate the type bar, and means operated by the lever for breaking the circuit immediately upon the actuation of the type bar. 115
17. In a key controlled mechanism, the combination of a key, an operated part, an electrically operated power mechanism arranged when operated to actuate the operated part, a normally open circuit including said power mechanism, means normally arranged to be operated by the key to close said circuit, means for disconnecting said circuit closing mechanism from the key, and means for directly connecting the key with the operated part. 120

tively with the typebars, the auxiliary lever connected with the typebar which is pivoted to the frame forward of its center, being pivoted to the frame at a point forward of the point at which the other auxiliary lever is pivoted, the two auxiliary levers having their forward ends substantially in line, and means for connecting the auxiliary levers respectively at their forward ends, with one of the key levers, means comprising coupling devices pivoted to the key levers, and arranged substantially in line for connecting the auxiliary levers respectively with the key levers, and a common means for holding both of said coupling devices in operative connection with their respective auxiliary levers.

22. In a key controlled mechanism, the combination of a key, an operated part, a lever coupled to the operated part for actuating it, an electrically operated power mechanism, controlled by the key, said electrically operated power mechanism comprising a magnet arranged in a normally open circuit a motor frame actuated by said magnet, a circuit closer in said circuit, comprising a stationary contact and movable contact, a push arm pivoted to said lever, and adapted to be moved into position to be struck by the motor frame, and means actuated by the key for moving the push arm into position to be struck by the motor frame and for operating the movable contact to close the circuit and means for operatively connecting the lever and key.

23. In a typewriting machine, the combination of a key, a typebar, a lever coupled to the typebar for operating it, an electrically operated power mechanism controlled by the key, said electrically operated power mechanism comprising a magnet arranged in a normally open circuit, a motor frame actuated by said magnet, a circuit closer in said circuit comprising a stationary contact and movable contact, a contact frame carrying the movable contact, a push arm, pivoted to said lever, and adapted to be moved into position to be struck by the motor frame, and means actuated by the key for moving the push arm into position to be struck by the motor frame and for operating the contact frame to close the circuit and means for operatively connecting the lever and the key.

24. In a key controlled mechanism, the combination of a plurality of keys, operated parts corresponding in number to the keys, a lever coupled to each of the operated parts for actuating it, an electrically operated power mechanism, controlled by the key, said electrically operated power mechanism including a magnet arranged in a normally open circuit, a motor frame actuated by the magnet, a circuit closer in said circuit comprising a stationary contact and

movable contact, a contact frame carrying the movable contact, a push arm pivoted to each of said levers, and adapted to be moved into position to be struck by the motor frame, and means connected to each of said keys for moving its push arm into position to be struck by the motor frame and for operating the contact frame to close the circuit and means for operatively connecting the lever and the key.

25. In a typewriting machine, the combination of a plurality of keys, typebars corresponding in number to the keys, a lever coupled to each of the typebars for operating it, an electrically operated power mechanism controlled by the key, said electrically operated power mechanism including a magnet arranged in a normally open circuit, a motor frame actuated by the magnet, a circuit closer in said circuit comprising a stationary contact and movable contact, a contact frame carrying the movable contact, a push arm pivoted to each of said levers, and adapted to be moved into position to be struck by the motor frame and means connected to each of said keys for moving its push arm into position to be struck by the motor frame and for operating the contact frame to close the circuit and means for operatively connecting the lever and the key.

26. In a key controlled mechanism, the combination of a key, an operated part, a lever coupled to the operated part for actuating it, electrically operated power mechanism interposed between said lever and key, comprising a normally open circuit, including a magnet a motor frame arranged to be actuated by the magnet, a stationary contact and a movable contact in the circuit, a contact frame, carrying the movable contact, a push arm connected with the lever, adapted to be moved into the path of the motor frame, and a device actuated by the key for positioning said push arm and for moving said contact frame to close the circuit, said device also serving to couple the key and lever, when the power mechanism is inactive.

27. In a typewriting machine the combination of a key, a typebar, a lever coupled to the typebar for operating it, electrically operated power mechanism interposed between said lever and key, comprising a magnet arranged in a normally open circuit, a motor frame arranged to be actuated by the magnet, a stationary contact and a movable contact in the circuit, a contact frame carrying the movable contact, a push arm connected with the lever adapted to be moved into the path of the motor frame and a device actuated by the key for positioning said push arm and for moving said contact frame to close the circuit, said device also serving to couple the key and the lever when the power mechanism is inactive.

28. In a typewriting machine, the combination of a key, a typebar, a lever coupled thereto for operating the same, electrically operated power mechanism interposed between said key and lever, comprising a magnet arranged in a normally open circuit, a motor frame arranged to be actuated by the magnet, a stationary contact and a movable contact in said circuit, a contact frame carrying the movable contact, a push arm connected with the lever, adapted to be moved into the path of the motor frame, and a device actuated by the key for positioning said push arm and for shifting the contact frame to close the circuit, said lever being arranged to disengage the device actuated by the key from said contact frame and positioned push arm upon the closing of the circuit when the machine is electrically operated and means for operatively connecting the lever and the key.

29. In a typewriting machine, the combination of a key, a typebar, and a lever coupled thereto for operating the same, electrically operated power mechanism interposed between said lever and key, comprising a magnet arranged in a normally open circuit, a motor frame actuated by the magnet, a stationary contact and a movable contact in said circuit, a contact frame carrying the movable contact, a push arm adapted to be moved into the path of the motor frame and a device actuated by the key for positioning said push arm and for shifting said contact frame to close the circuit, and coacting elements carried by the lever and the device actuated by the key, for releasing said contact frame and positioned push arm in the downward movement of said lever and means for operatively connecting the lever and the key.

30. In a typewriting machine, the combination of a key, a typebar, and a lever coupled thereto for operating the same, electrically operated power mechanism interposed between said lever and key, comprising a magnet arranged in a normally open circuit, a motor frame actuated by the magnet, a stationary contact and a movable contact in said circuit, a contact frame carrying the movable contact, a push arm adapted to be moved into the path of the motor frame and a device actuated by the key for positioning said push arm and for shifting said contact frame to close the circuit, a fixed part on said device carried by the key and a beveled surface on said lever coacting with said fixed part to throw said device carried by the key out of engagement with the contact frame and positioned push arm.

31. In a key controlled mechanism, the combination of an operated part, a key, a key lever carrying the same, a supplemental lever coupled to the operated part, electrically operated mechanism comprising a mo-

tor frame, a push arm connected with the supplemental lever adapted to be operated by the motor frame, a motor arranged in a normally open circuit, a stationary contact and a contact frame carrying a movable contact, means carried by the key lever for positioning said push arm relative to the motor frame and for actuating said contact frame to close the circuit and means for operatively connecting the supplemental lever and the key lever.

32. In a typewriting machine a typebar, a key, a key lever carrying the same, a supplemental lever coupled to the typebar, electrically operated mechanism comprising a motor frame, a push arm connected with said supplemental lever adapted to be operated by the motor frame, a motor arranged in a normally open circuit, a stationary contact, and a contact frame carrying a movable contact, means carried by said key lever for positioning said push arm relative to the motor frame, and for actuating said contact frame to close the said circuit and means for operatively connecting the supplemental lever and the key lever.

33. In a typewriting machine and in combination, a typebar, a key, a key lever carrying the same, a supplemental lever coupled to the typebar, electrically operated mechanism comprising a motor frame, a push arm to be operated thereby associated with said supplemental lever, and a motor, stationary contact and contact frame carrying a contact member included in a normally open circuit, and a member pivoted to the key lever proper having shoulders engaging the said push arm and contact frame.

34. In a typewriting machine and in combination, a typebar, a key, a key lever carrying the same, a supplemental lever coupled to the typebar, electrically operated mechanism comprising a motor frame, a push arm to be operated thereby associated with said supplemental lever, a motor, a stationary contact and a contact frame carrying a contact member included in a normally open circuit, and a member pivoted to the key lever proper having shoulders engaging said push arm and contact frame, said member being also adapted to serve as a coupling link between said key lever proper and the supplemental lever when the electrically operated mechanism is thrown out of action.

35. In a typewriting machine, and in combination, a typebar, a key, a key lever carrying the same, a supplemental lever coupled to the typebar, electrically operated mechanism comprising a motor frame, a push arm to be operated thereby associated with said supplemental lever, a motor, a stationary contact and a contact frame carrying a contact member included in a normally open circuit, and a member pivoted

to the key lever proper having shoulders arranged to engage said push arm and contact frame, said member being also adapted to serve as a coupling link between said key lever proper and the supplemental lever when the electrically operated mechanism is thrown out of action, and means for shifting said contact frame out of the path of said member pivoted to the key lever proper 10 when the electrically operated mechanism is out of action.

36. In a typewriting machine, and in combination, a typebar, a key, a key lever carrying the same, a supplemental lever coupled to the typebar, electrically operated power mechanism comprising a motor frame, a push arm arranged to be operated thereby associated with said supplemental lever, a motor, a stationary contact and a contact 15 frame carrying a contact member included in a normally open circuit, and a member pivoted to the key lever proper having shoulders engaging said push arm and contact frame, said member being also adapted 20 to serve as a coupling link between said key lever proper and the supplemental lever when the electrically operated power mechanism is thrown out of action, and means for holding said member in position to prevent the disengagement thereof from said supplemental lever.

37. In a typewriting machine, a typebar, a key, a key lever carrying the same, a supplemental lever coupled to the typebar, electrically operated mechanism comprising a motor frame, a push arm adapted to be operated thereby associated with said supplemental lever, a motor, a stationary contact and a contact frame carrying a movable 25 contact member included in a normally open circuit, and a member carried by said key lever proper for positioning said push arm relative to the motor frame and for actuating said contact frame to close said circuit, and means for releasing said contact frame and positioned push arm from said member after the supplemental lever is actuated to permit the parts to reassume their initial positions independently of the other.

38. In a typewriting machine, and in combination, a typebar, a key, a key lever proper, a supplemental lever, an upwardly extending arm pivoted to the supplemental lever, a coupling between the supplemental lever 35 and typebar, a motor frame operating upon the push arm, electrically operated mechanism for actuating the motor frame, comprising a motor, a stationary contact and a contact frame carrying a contact member arranged in a normally open circuit and a device pivoted to the key lever proper coacting with the contact frame and push arm to position the latter and actuate said contact frame to close the circuit when the key lever proper is depressed.

39. In a typewriting machine, and in combination, a typebar, a key, a key lever proper, a supplemental lever, a push arm pivoted to the supplemental lever, a coupling between the supplemental lever and typebar, a motor frame operating upon the push arm, electrically operated mechanism for actuating the motor frame comprising a motor, a stationary contact and a contact frame carrying a contact member arranged in a normally open circuit, a device pivoted to the key lever proper having rearwardly extending engaging parts coacting with the contact frame and push arm, respectively, yielding means for throwing said device in engaging position, and means for throwing said device out of engagement. 70

40. In a typewriting machine, and in combination, a typebar, a key, a key lever proper, a supplemental key lever, a link connection between the same and said typebar, a second lever pivoted to the supplemental lever having a setting member and an upwardly extending arm, a motor frame coacting with the latter, electrically operated mechanism for actuating the motor frame including a normally open circuit, a contact frame adapted to close said circuit, means carried by the key lever proper coacting with the setting member of the second lever and said contact frame for throwing the upwardly extending arm of the second lever into the path of the motor frame, and for operating said contact frame to close said circuit when said key lever proper 80 is depressed and means for operatively connecting the supplemental key lever and key lever proper. 90

41. In a typewriting machine, and in combination, a typebar, a key, a key lever proper, a supplemental key lever, a link connection between the same and said typebar, a second lever pivoted to the supplemental lever having a setting member provided with a lateral extension projecting over the edge of the supplemental lever, and also provided with an upwardly extending arm, a motor frame coacting with the latter, electrically operated mechanism for actuating the motor frame including a normally open 105 circuit, a contact frame adapted to close said circuit, and means carried by the key lever proper coacting with the lateral extension of the setting member of said second lever and said contact frame for throwing the upwardly extending arm of the second lever into the path of the motor frame and for operating the contact frame to close said circuit when said key lever is depressed. 110

42. In a typewriting machine the combination with a typebar, a key, a key lever carrying the same, a supplemental lever coupled to said typebar electrically operated means for depressing said supplemental 120 125 130

lever including a motor frame, and a contact frame located in a normally open circuit, a push arm associated with the supplemental lever arranged to be actuated by the motor frame to depress the supplemental lever, a member carried by the key lever proper for positioning the push arm and actuating the contact frame when the key lever proper is depressed, means for throwing said member out of engagement with said push arm and a device for holding said member locked in engagement with said push arm and the latter in engagement with the supplemental lever, said device being also arranged to serve as a stop for the key lever proper.

43. In a typewriting machine, the combination with a typebar, a key, a key lever carrying the same a supplemental lever coupled to said typebar electrically operated means for depressing said supplemental lever including a motor frame and a contact frame located in a normally open circuit a push arm associated with the supplemental lever arranged to be actuated by the motor frame to depress the supplemental lever a member carried by the key lever proper for positioning the push arm and actuating the contact frame when the key lever proper is depressed, means for throwing said member out of engagement with said push lever, and a rocking cross bar for holding said member locked in engagement with said push arm and the latter in engagement with the supplemental lever, said rocking cross bar being also arranged to serve as a stop for the key lever proper.

44. In a typewriting machine, the combination with a typebar, a key, a key lever carrying the same, a supplemental lever coupled to said typebar, electrically operated means for depressing said supplemental lever including a motor frame, a contact frame located in a normally open circuit, a push arm associated with the supplemental lever arranged to be actuated by the motor frame to depress the supplemental lever, a member carried by the key lever proper for positioning the push arm and actuating the contact frame when the key lever proper is depressed means for throwing said member out of engagement with said push arm, comprising a device having two working faces, so arranged that one of said faces when in action holds said member locked in engagement with the push arm and serves as a stop for arresting the key levers in the return thereof and the other face of said device when in action arrests said key levers in a relatively higher plane.

45. In a typewriting machine, the combination with a typebar, a key, a key lever carrying the same, a supplemental lever coupled to said typebar, electrically operated means for depressing said supplemental

lever including a motor frame and a contact frame located in a normally open circuit, a push arm associated with a supplemental lever arranged to be actuated by the motor frame to depress the supplemental lever, a member carried by the key lever proper for positioning the push arm and actuating the contact frame when the key lever proper is depressed, means for throwing said member out of engagement with said push arm, and a movable carrier for said contact frame to shift the latter out of the path of said member.

46. In a typewriting machine, the combination with a typebar, a key, a key lever carrying the same, a supplemental lever coupled to said type-bar, electrically operated means for depressing said supplemental lever including a motor frame and a contact frame located in a normally open circuit, a push arm associated with the supplemental lever arranged to be actuated by the motor frame to depress the supplemental lever, a member carried by the key lever proper for positioning the push arm and actuating the contact frame when the key lever proper is depressed, means for throwing said member out of engagement with said push arm and a pivoted carrier for the contact frame adapted to be rocked to shift said frame out of the path of said member.

47. In a typewriting machine, the combination with a type bar, a key, a key lever proper, a supplemental lever coupled to the type bar, a motor arranged, when operated, to depress the supplemental lever, means controlled by the key for actuating the motor and means for releasing the supplemental lever to permit its return to initial position, independent of the key lever proper, separate springs associated with the levers to restore the same to initial position, means for operatively coupling the supplemental lever to the key lever proper, and means for throwing out of operation the return spring associated with one of said levers.

48. In a typewriting machine, the combination of a type bar, a key, a key lever proper, a supplemental lever coupled to the type bar, a motor arranged, when actuated, to depress the supplemental lever, means controlled by the key for actuating the motor, and means for releasing the supplemental lever to permit of its independent return to initial position, independent of the movement of the key lever proper, separate springs associated with the levers to restore the same to initial position, means for coupling the levers together to secure an interdependent movement thereof, and means for throwing out of operation the return spring associated with the key lever proper.

49. In a typewriting machine, the combi-

- 5 nation with a type bar, a key, a key lever proper, a supplemental lever coupled to the type bar, a motor arranged, when actuated, to depress the supplemental lever, means controlled by the key lever for actuating the motor, means for releasing the supplemental lever to permit its return to initial position, independent of the key lever proper, separate springs associated with the levers to 5
10 restore the same to initial position, a rocking bar carrying the spring associated with the key lever proper and means for tilting said bar to throw the spring carried thereby out of operation.
- 15 50. In combination in a typewriting machine, a typebar, a key, a lever coupled to said bar, and electrically operated mechanism for depressing said lever to operate the typebar when the key pertaining thereto is depressed including a motor frame, a normally deenergized motor for drawing the frame downward, a device located below the motor frame and normally out of the path thereof connected to said lever, and means 20
25 for shifting said device into the path of the motor frame when the key is depressed, and for energizing said motor, whereby the motor frame will strike downwardly and depress said device and means for operatively connecting the lever and the key.
51. In a typewriting machine and in combination, a pivoted typebar, a key, a key lever proper pivoted at its rear end, a supplemental lever, a link connection between the same and the typebar, a second lever pivoted to the supplemental lever near the free end thereof, having a horizontal and a vertical member, said horizontal member having an extension designed to rest upon the edge 30
35 of the lever, a motor, a normally open circuit including a generating unit, a contact frame adapted to close the circuit, a pivoted frame carrying the latter, said frame also carrying a shifting and supporting bar arranged to coact with said second lever, an arm pivoted at its lower end to the key lever proper, and extending upwardly therefrom, said arms having shoulders engaging respectively the contact frame and the extension of the horizontal member of the second lever, and means for throwing said arm into a position to provide a direct engagement between the same and said extension and the latter and its lever, whereby the 40
45 supplemental lever and the key lever are coupled together to move without lost motion.
52. In a key controlled mechanism, the combination of an operated part, a key lever, an auxiliary lever and means connecting the auxiliary lever with the operated part, of power mechanism adapted, when actuated, to operate the auxiliary lever, means for controlling the power mechanism, an arm connected with the key lever, adapted, when 50
55
60
65

in one position, to operate the controlling means on the depression of the key, and when in another position, to mechanically connect the key lever and auxiliary lever, and means for shifting the arm from one of its positions to the other.

53. In a typewriting machine, the combination of a typebar, a key lever, an auxiliary lever and means connecting the auxiliary lever with the typebar, of power mechanism adapted, when actuated, to operate the auxiliary lever, means for controlling the power mechanism, an arm connected with the key lever, adapted, when in one position to operate the controlling means on the depression of the key and when in another position to mechanically connect the key lever and auxiliary lever, and means for shifting the arm from one of its positions to the other.

54. In a key controlled mechanism, the combination of an operated part, a key lever, an auxiliary lever and means connecting the auxiliary lever with the operated part, of electric power mechanism adapted, when actuated, to operate the auxiliary lever, means for controlling the electric power mechanism, an arm connected with the key lever, adapted, when in one position, to operate the controlling means on the depression of the key, and when in another position, to mechanically connect the key lever and auxiliary lever, and means for shifting the arm from one of its positions to the other.

55. In a typewriting machine, the combination of a typebar, a key lever, an auxiliary lever and means connecting the auxiliary lever with the typebar, of electric power mechanism adapted, when actuated, to operate the auxiliary lever, means for controlling the electric power mechanism, an arm connected with the key lever, adapted, when in one position, to operate the controlling means on the depression of the key, and when in another position, to mechanically connect the key lever and auxiliary lever, and means for shifting the arm from one of its positions to the other.

56. In a key controlled mechanism, the combination of an operated part, a key lever, an auxiliary lever and means connecting the auxiliary lever with the typebar, of a normally inactive motor, adapted, when actuated, to operate the auxiliary lever, means for actuating the motor, an arm connected with the key lever adapted, when in one position, to operate the motor actuating means on the depression of the key, and when in another position, to mechanically connect the key lever and auxiliary lever, and means for moving the controlling means into and out of operative position and for shifting the arm from one of its positions to the other.

57. In a typewriting machine, the combination of a typebar, a key lever, an auxiliary

- lever and means connecting the auxiliary lever with the typebar, of a normally inactive motor adapted, when actuated, to operate the auxiliary lever, means for actuating the motor, an arm connected with the key lever, adapted, when in one position, to operate the motor actuating means on the depression of the key, and when in another position, to mechanically connect the key lever and auxiliary lever, and means for shifting the arm from one of its positions to the other. 5
58. In a key controlled mechanism, the combination of an operated part, a key lever, an auxiliary lever and means connecting the auxiliary lever with the operated part, of a power mechanism adapted, when actuated, to operate the auxiliary lever, means for controlling the power mechanism, an arm 10 pivotally connected with the key lever, adapted, when in one position, to operate the controlling means on the depression of the key, and when in another position, to mechanically connect the key lever and auxiliary lever, and means for shifting the arm from one of its positions to the other. 15
59. In a key controlled mechanism, the combination of an operated part, a key lever, an auxiliary lever and means connecting the auxiliary lever with the operated part, a normally inactive motor adapted, when actuated, to operate the auxiliary lever, means for actuating the motor, an arm pivotally 20 connected with the key lever, adapted, when in one position, to operate the motor actuating means on the depression of the key, and when in another position, to mechanically connect the key lever and auxiliary lever, and means for shifting the arm from one of its positions to the other. 25
60. In a typewriting machine, the combination of a typebar, a key lever, an auxiliary lever and means connecting the auxiliary lever with the typebar, of a normally inactive motor adapted, when actuated, to operate the auxiliary lever, means for actuating the motor, an arm pivotally 30 connected with the key lever, adapted, when in one position, to operate the motor actuating means on the depression of the key, and when in another position, to mechanically connect the key lever and auxiliary lever, and means for shifting the arm from one of its positions to the other. 35
61. In a key controlled mechanism, the combination of an operated part, a key lever, an auxiliary lever and means connecting the auxiliary lever with the operated part, of a motor magnet arranged in a normally open circuit adapted, when actuated, to operate the auxiliary lever, circuit closing means for closing the motor circuit, an arm connected 40 with the key lever, adapted, when in one position, to operate the circuit closing means on the depression of the key, and when in another position, to mechanically connect the key lever and auxiliary lever, and means for shifting the arm from one of its positions to the other. 45
62. In a typewriting machine, the combination of a typebar, a key lever, an auxiliary lever and means connecting the auxiliary lever with the typebar, of a motor magnet arranged in a normally open circuit adapted, when actuated, to operate the auxiliary lever, circuit closing means for closing the motor circuit, an arm connected 50 with the key lever, adapted, when in one position, to operate the circuit closing means on the depression of the key, and when in another position, to mechanically connect the key lever and auxiliary lever, and means for shifting the arm from one of its positions to the other. 55
63. In a key controlled mechanism, the combination of an operated part, a key lever, an auxiliary lever and means connecting the auxiliary lever with the operated part, of a normally inactive motor adapted, when actuated, to operate the auxiliary lever, means for actuating the motor, an arm pivotally 60 connected with the key lever, adapted, when in one position, to operate the motor actuating means on the depression of the key, and when in another position, to mechanically connect the key lever and auxiliary lever, and means for shifting the arm from one of its positions to the other. 65
64. In a typewriting machine, the combination of a typebar, a key lever, an auxiliary lever and means connecting the auxiliary lever with the typebar, of a normally inactive motor adapted when actuated to operate the auxiliary lever, means for actuating the motor, an arm pivotally 70 connected with the key lever, adapted, when in one position, to operate the motor actuating means on the depression of the key, and when in another position, to mechanically connect the key lever and auxiliary lever, and means for shifting the arm from one of its positions to the other. 75
65. In a key controlled mechanism, the combination of an operated part, a key lever, an auxiliary lever and means connecting the auxiliary lever with the operated part, of a motor magnet arranged in a normally open circuit adapted, when actuated, to operate the auxiliary lever, means for closing the motor circuit, an arm pivotally 80 connected with the key lever, adapted, when in one position, to operate the circuit closing means on the depression of the key, and when in another position, to mechanically connect the key lever and auxiliary lever, and means for shifting the arm from one of its positions to the other. 85
66. In a typewriting machine, the combination of a typebar, a key lever, an auxiliary lever and means connecting the aux- 90

- iliary lever with the type bar, of a motor magnet arranged in a normally open circuit, adapted, when actuated, to operate the auxiliary lever, means for closing the motor circuit, an arm connected with the key lever adapted when in one position, to operate the circuit closing means on the depression of the key, and when in another position, to mechanically connect the key lever and auxiliary lever, and means for shifting the arm from one of its positions to the other. 70
67. In a key controlled mechanism, the combination of an operated part, a key lever, an auxiliary lever and means connecting the auxiliary lever with the operated part, of power mechanism adapted, when actuated, to operate the auxiliary lever, means for controlling the power mechanism arranged to be movable into and out of operative position, an arm connected with the key lever adapted, when in one position, to operate the controlling means on the depression of the key, and when in another position, to mechanically connect the key lever and auxiliary lever, means for moving the controlling means into and out of operative position, and means for shifting the arm from one of its positions to the other. 75
68. In a typewriting machine, the combination of a typebar, a key lever, an auxiliary lever and means connecting the auxiliary lever with the typebar, of power mechanism adapted, when actuated, to operate the auxiliary lever, means for controlling the power mechanism arranged to be movable into and out of operative position, an arm connected with the key lever adapted, when in one position, to operate the controlling means on the depression of the key, and when in another position to mechanically connect the key lever and auxiliary lever, means for moving the controlling means into and out of operative position, and means for shifting the arm from one of its positions to the other. 80
69. In a key controlled mechanism, the combination of an operated part, a key lever, an auxiliary lever and means connecting the auxiliary lever with the operated part, of a normally inactive motor adapted, when actuated, to operate the auxiliary lever, means for actuating the motor, an arm pivotally connected with the key lever, adapted, when in one position, to operate the motor actuating means on the depression of the key, and when in another position, to mechanically connect the key lever and auxiliary lever, and means for swinging the arm on its pivot from one of its positions to the other. 85
70. In a typewriting machine, the combination of a typebar, a key lever, an auxiliary lever and means connecting the auxiliary lever with the typebar, of a normally inactive motor adapted, when actuated, to operate the auxiliary lever, means for actuating the motor, an arm pivotally connected with the key lever, adapted, when in one position, to operate the motor actuating means on the depression of the key, and when in another position, to mechanically connect the key lever and auxiliary lever, and means for swinging the arm on its pivot from one of its positions to the other. 90
71. In a typewriting machine, the combination of a platen, a printing device, a key-lever, a source of power, operative connections between said source of power and said printing device controlled by said key-lever, said key-lever being otherwise independent of said source of power and of said operative connections and mechanically disconnected from the printing device and connections between said key-lever and said printing device whereby said printing device may be actuated directly by said key-lever, substantially as described. 95
72. In a typewriting machine, the combination of a platen, a printing device, a key-lever, a direct connection between said key-lever and said printing device and means to couple the same to the key lever, a source of power, operative connections between said source of power and said printing device normally disconnected, and means controlled by said key-lever to engage said connections, said key-lever being otherwise independent of said source of power and of said operative connections and mechanically disconnected from the printing device, substantially as described. 100
73. In a typewriting machine, the combination of a platen, a printing device, a key-lever, an electromagnetic device included in a normally open circuit, means controlled by the key-lever to close said circuit, operative connections between said electromagnetic device and said printing device, said key-lever being otherwise independent of said electromagnetic device and of said operative connections and mechanically disconnected from the printing device and connections between said key-lever and printing device, whereby said printing device may be actuated directly by said key-lever, substantially as described. 105
74. In a typewriting machine, the combination of a platen, a printing device, an electromagnetic device included in a normally open circuit, means controlled by the key-lever to close said circuit, means controlled by the key lever to establish operative mechanical connections between said electromagnetic device and the printing device, said key-lever being otherwise independent of said electromagnetic device and of said operative connections and mechanically disconnected from the printing device and connections between said key-lever and print- 110

ing device whereby said printing device may be actuated directly by said key-lever, substantially as described.

75. In a typewriting machine, the combination of a platen, a printing device, including a type bar lever, a key lever, a secondary lever engaging said type bar lever, and means to couple said secondary lever to said key lever, whereby the printing device may be actuated directly by said key lever.

76. In a typewriting machine, the combination of a platen, a printing device, a key lever, a source of power, operative connections between the source of power and the printing device controlled by the key lever, and means operating through a part of said connections for operating the printing device directly from the key lever.

77. In a key-controlled mechanism, the combination of a key lever and an operated part, a supplemental lever connected with said operated part, a normally inactive motor device, a bell crank lever pivoted to said supplemental lever, an actuating arm pivoted to the key lever and adapted to engage one arm of the bell crank lever, and to impart motion thereto upon the depression of the key lever, the other arm of said bell crank lever when actuated being brought into position to actuate the supplemental lever from said motor device, means controlled by the key lever to bring the motor device into action, and means automatically acting an instant after the depression of a key lever to render said motor device inactive in advance of any upward movement of the key lever.

78. In a key-controlled mechanism, the combination of a key lever and an operated part, a supplemental lever connected with said operated part, a normally inactive motor device, a bell crank lever pivoted to said supplemental lever, an actuating arm pivoted to the key lever and adapted to engage one arm of the bell crank lever and to impart motion thereto upon the depression of the key lever, the other arm of said bell crank lever when actuated being brought into position to actuate the supplemental lever from said motor device, means controlled by the key lever to bring the motor device

into action, and means acting an instant after the depression of a key lever to render said motor device inactive to remain inactive until another key depression even though the key previously depressed be held in its depressed position.

79. In a key-controlled mechanism, the combination of a key lever and an operated part, a supplemental lever connected with said operated part, a normally inactive motor device, a bell crank lever pivoted to said supplemental lever, an actuating arm pivoted to the key lever and adapted to engage one arm of the bell crank lever, and to impart motion thereto upon the depression of the key lever, the other arm of said bell crank lever when actuated being brought into position to actuate the supplemental lever from said motor device, means controlled by the key lever to bring the motor device into action, and means automatically operated by the movements of the motor device and in advance of any upward movement of the key lever, for rendering said motor device again inactive, after having once actuated said operated part.

80. In a key-controlled mechanism, the combination of a key lever and an operated part, a supplemental lever connected with said operated part, a normally inactive motor device, a bell crank lever pivoted to said supplemental lever, an actuating arm pivoted to the key lever and adapted to engage one arm of the bell crank lever and to impart motion thereto upon the depression of the key lever, the other arm of said bell crank lever when actuated being brought into position to actuate the supplemental lever from said motor device, contacts controlled by the key lever to bring the motor device into action, and means actuated by the movements of the motor device for releasing the contacts.

In testimony whereof, I have hereunto signed my name in the presence of two attesting witnesses, at Washington, in the District of Columbia, this 30th day of August, 1902.

JOHN T. SCHAAFF.

Witnesses:

W.M. J. WHALLEY,
HENRY E. COOPER.
